CLAIM

The ornamental design for a pocketed brassiere as shown and described.

DESCRIPTION

FIG. 1 is a front view of a pocketed brassiere showing my new design;

FIG. 2 is a rear view of the pocketed brassiere;

FIG. 3 is a right side view of the pocketed brassiere;

FIG. 4 is a left side view of the pocketed brassiere;

FIG. 5 is a top view of the pocketed brassiere;

FIG. 6 is a bottom view of the pocketed brassiere;

FIG. 7 is a top rear side perspective view of the pocketed brassiere; and,

FIG. 8 is a top rear side perspective view of the pocketed brassiere with pockets in use.

The broken lines in FIG. 8 are illustrative of environmental structures positioned in the pockets and forming no part of the claimed design. The broken lines in the drawing figures on the article are illustrative of stitching forming no part of the claimed design.

1 Claim, 6 Drawing Sheets
